CLAIM

The ornamental design for a lavatory, as shown and described.

DESCRIPTION

FIG. 1 is a top, front perspective view of a lavatory embodying our new design;

FIG. 2 is a top plan view thereof;

FIG. 3 is a bottom plan view thereof;

FIG. 4 is a front elevational view thereof, the rear, left side, and right side elevational views being identical to the front elevational view shown;

FIG. 5 is a cross-sectional view taken along line 5—5 of FIG. 2;

FIG. 6 is a top, front perspective view of a second embodiment;

FIG. 7 is a top plan view thereof;

FIG. 8 is a bottom plan view thereof;

FIG. 9 is a first elevational view thereof, the rear, left side, and right side elevational views being identical to the front elevational view shown; and,

FIG. 10 is a cross-sectional view taken along line 10—10 of FIG. 7.
